FOREIGN PATENT DOCUMENTS

EP 1142526 A1 10/2001

* cited by examiner

Primary Examiner — John Windmuller(74) *Attorney, Agent, or Firm* — Banner & Witcoff, Ltd.(57) **CLAIM**

The ornamental design for a mop head, as shown and described.

DESCRIPTION

FIG. 1 is a top, front, right perspective view of a mop head showing my new design;

FIG. 2 is a front view thereof;

FIG. 3 is a right side view thereof;

FIG. 4 is a rear view thereof;

FIG. 5 is a left side view thereof; and,

FIG. 6 is a top view thereof.

The uneven-length broken lines represent unclaimed boundaries of the claimed design. The even-length broken lines showing the remainder of the mop head are for environmental purposes only and form no part of the claimed design.
